(57) **CLAIM**

The design for a dorsal blocking splint, as shown and described.

DESCRIPTION

FIG. 1 is a bottom view of our new dorsal blocking splint design;

FIG. 2 is a top plan view of our new dorsal blocking splint design;

FIG. 3 is a left side elevational view;

FIG. 4 is a right side elevational view;

FIG. 5 is distal end view;

FIG. 6 is a proximal end view;

FIG. 7 is a perspective view of the top as seen from the proximal end;

FIG. 8 is a perspective view of the top as seen from the distal end;

FIG. 9 is a perspective view of the bottom as seen from the distal end;

FIG. 10 is a perspective view of the bottom as seen from the proximal end with the straps removed from the splint;

FIG. 11 is a perspective view of the bottom as seen from the distal end with the straps removed;

FIG. 12 is a perspective view of the top as seen from the distal end with the straps removed;

FIG. 13 is a top perspective view as seen from the proximal end with the straps removed;

FIG. 14 is a bottom view of the splint with the straps removed; and,

FIG. 15 is a top plan view of the splint with the straps removed.

The broken lines inside the solid lines of the drawing figures indicate shading in the splint material.
